UNITED STATES PATENT OFFICE.

CHARLES R. WOOD, OF DETROIT, MICHIGAN.

SAFETY POCKET.

Application filed September 8, 1926. Serial No. 134,230.

This invention relates to safety pockets and more particularly to an improvement in pockets of the type illustrated in my prior Patent, No. 1,431,275, granted October 10, 5 1922, and reissued as No. 15,646, under date of July 10, 1923.

An important object of the invention is to improve the construction of this prior patent in such manner that the pocket may be 10 much more readily assembled and a great amount of material ordinarily wasted in the cutting of the garment is saved.

A further and more specific object of the invention is to provide in a front or swinging pocket construction, wherein the entrance opening to the pocket is slanting, a construction such that the material ordinarily removed to properly position the slanting opening of the pocket is employed 15 20 in the formation of a lock, preventing loss of the contents of the pocket.

These and other objects I attain by the construction shown in the accompanying drawings, wherein for the purpose of illustration is shown a preferred embodiment of 25 my invention and wherein:—

Figure 1 is a side elevation of the upper portion of the leg of a garment embodying a pocket constructed in accordance with my 30 invention;

Figure 2 is a fragmentary front elevation of the upper portion of a front leg section illustrating the manner in which the flap 25 is produced;

Figure 3 is an inside elevation partially broken away of a pocket showing the flap after the operation of securing the pocket thereto has been completed;

Figure 4 is a similar view of the pocket 40 with the facing piece in position;

Figure 5 is a section on the line 5—5 of Figure 3;

Figure 6 is a section on the line 6—6 of Figure 4;

Figure 7 is a section on the line 7—7 of Figure 4;

Figure 8 is a plan of the blank from which the pocket is formed;

Figure 9 is a view showing a modified 50 manner of connecting the lower edges of the flap and facing piece to the front wall of the pocket.

Referring now more particularly to the drawings, the numeral 10 designates the leg

section of trousers or overalls having a top edge 11 and a side edge 12 substantially perpendicularly related with relation to one another. At the junction of these edges in the formation of the garment, a pocket opening is formed and where this pocket 55 opening is slanting and arranged upon the line substantially indicated by the dotted line 13 of Figure 2, the material is usually cut away upon a line substantially indicated by the dotted line 14, with the result 60 that a triangular piece of material lying outwardly of the dotted line 14 and too small to be of any use in the construction of the garment becomes waste and represents 65 so much loss to the manufacturer.

In accordance with my invention, where the pocket opening is to be located upon the line 13, I cut away the corner formed by the perpendicularly related edges 11 and 12 70 upon a line 15 well spaced from the line 13, 75 so that a very small waste section 16 is formed. From the edges 11 and 12, I form perpendicularly disposed slits or notches 17 intersecting the line 13 substantially at the lines 18 and 19 which represent lines of 80 stitching by which the edges 11 and 12 of the sections 10 are eventually secured to the waist-band and back leg section of the complete garment. The pocket blank 20 is originally in the form of a rectangle, the two 85 lower corners 21 of which are rounded and one upper corner of which is cut away at the angle of the pocket opening, as indicated at 22. This blank is folded centrally between its side edges upon a line 23 and the 90 lower edges thereof stitched to one another, as indicated at 24. The material or flap 25 lying outwardly of the line 13 between the inner ends of the notches 17 is then suitably finished at its free edge by reverting and 95 stitching the same, as indicated at 26, and then folded back upon the line 13. The edge 22 of the outer wall 27 of the pocket blank is then inserted between the flap 25 and the wall of the garment proper and a 100 double row of stitching, generally indicated at 28, employed to connect the pocket in the proper position. A flap is thus provided extending between the inner and outer walls of the pocket and consisting of a continuation of the outer wall of the garment.

A substantially triangular facing piece 29 of the same material as the garment wall is

provided, this piece having a rectangular corner 30, the opposed side edge 31 spaced from this rectangular corner a distance greater than the distance between the line 13 and the point which would be formed by the intersection of the edges 11 and 12 of the garment wall. This piece of material is then placed, so that the sides forming the rectangular corner provide continuations of the sides 11 and 12 and the inner edge 31 thereof is arranged between the walls of the pocket. At points adjacent the upper and lower ends of the slanting edge 32, this piece is secured to the garment wall, the outer wall 27 of the pocket and the flap 25 by bar tackings 34 and 35, which define the upper and lower edges of the pocket opening.

Below the lower bar tacking 35, the piece 29 is further secured by stitching 36 following the stitchings 28 by means of which the pocket is secured between the outer wall of the garment and the flap 25. The flap 25 and the portion of the piece 29 lying inwardly of the edge 32 are then secured together along the upper edge of the flap 25 by stitching 37 and a second row of stitching 38 is extended from the bar tacking 35 inwardly and downwardly across the flap 25 and the inwardly extending portion of the piece 29, this row of stitching likewise extending through the front wall of the pocket, so that at their lower ends, the flap and inwardly extending portion of the piece 29 are secured not only to one another, but to the front pocket wall. This procedure produces a fabric tube extending into the pocket from the pocket opening, the lower end of this tube being connected to the front wall of the pocket and the upper end of the tube free to separate from this wall. This results in articles which are introduced through the tube, if the garment be inverted, being directed by the stitching or connection of the lower end of the tube with the front pocket wall, to one side of the tube, with the result that the contents do not escape from the pocket, but are held therein. At the same time, the amount of fabric employed in the construction of the garment is only slightly greater than that ordinarily employed and a considerable amount of waste is avoided. It is pointed out that where the flap 25 is not employed in the construction of the lock, it would be necessary to substitute for this flap, if an efficient pocket is to be produced, a sail cloth or pocket material flap which would not have the stiffness or wearing qualities of the material used in the formation of the garment and which would, when the pocket had any tendency whatever to stand open, present an unsightly appearance, thus detracting from the value of the garment, particularly when employed in trousers.

Attention is further directed to the fact

that the hand may be introduced to the bottom of the pocket through the tube without any unnecessary bending or flexing movements thereof, thus enabling ready access to the articles when it is desired to remove them, due to the fact that a line bisecting the angle between the stitchings 37 and 38 intersects the bottom 40 of the pocket instead of the side wall 41 thereof, as in all prior constructions with which I am familiar. In the form shown in Figure 9, the stitching 38 is dispensed with and a row of stitching 39 employed for connecting the facing piece 29 to the front wall of the pocket. Where this construction is employed, bar tacking 40 is used to connect the lower corner of the flap 25 to the front wall. Since, by the construction previously described, one sewing operation is unnecessary this first described construction is preferred.

Since the construction hereinbefore set forth is obviously capable of a certain range of change and modification without materially departing from the spirit of the invention, I do not limit myself to such specific structure except as hereinafter claimed.

I claim:

1. In combination with a pocket having an opening, two pieces of material extending into the pocket at the opening and having their inner edges spaced transversely of the pocket from the pocket opening, said pieces of material being free from connection with one another at the pocket opening, stitching connecting said pieces of material to one another and extending inwardly from the upper edge of the pocket opening while leaving said pieces free from the walls of the pocket, the lower ends of said pieces being secured to one wall of the pocket at the lower end of the pocket opening.

2. In a safety pocket construction for garments and in combination with the front leg section of a garment, a pocket supported thereby, the pocket opening being at an angle to the top and side edges of the leg section, the material of the leg section between the junction of the side and top edges of the leg section and the pocket opening being folded into the pocket and being secured to the front wall of the pocket at its lower end and free along its inner edge to provide a lock flap.

3. In a safety pocket construction for garments and in combination with the front leg section of a garment, a pocket supported thereby, the pocket opening being at an angle to the top and side edges of the leg section, the material of the leg section between the junction of the side and top edges of the leg section and the pocket opening being folded into the pocket to provide a lock flap, the flap being secured to the front wall of the pocket at its lower end, and a piece of material having a portion extending into the

5 pocket from the opening and forming a second lock flap, said second lock flap at the upper edge of the pocket opening being secured to the first named lock flap by stitching extending into the pocket from the opening and at the lower edge of the pocket opening being secured to the front wall of

the pocket by stitching extending into the pocket from the opening and across the lower end of the first named lock flap. 10

In testimony whereof I hereunto affix my signature.

CHARLES R. WOOD.
